GARMENT HANGER

George Daniel Strampe, 513 Wingra St., Madison, Wis.
Filed June 7, 1962, Ser. No. 200,861
10 Claims. (Cl. 223—87)

This invention relates to garment hangers and more particularly to hangers adapted to support coats or other upper garments with or without shoulders, and/or trousers, either singly or in combination.

It is a primary object of the present invention to provide a garment hanger which is adapted to support a wide variety of garments on non-crushable, relatively large diameter support surfaces without wrinkling such garments.

It is a further object of the present invention to provide an inexpensive garment hanger which may be fabricated from a single sheet of low cost material with a minimum of waste.

It is a still further object of the present invention to provide a garment hanger having self-locking support means which will provide a more positive locking action as the load on the hanger is increased.

It is another object of the present invention to provide a low cost garment hanger which requires no staples, glue, rivets, or other external fastening means to assemble.

It is an additional object of the present invention to provide a garment hanger which is easily assembled and disassembled.

Other objects and advantages of the present invention will be readily apparent from the following detailed description taken in conjunction with the accompanying drawings wherein a preferred embodiment of the present invention has been selected for exemplification.

In the drawings:

FIG. 1 is a front elevation view of the body portion of my improved garment hanger in its disassembled form.

FIG. 2 is a front elevation view of the improved garment hanger of my invention in its assembled form.

FIG. 3 is a rear view of my assembled garment hanger.

FIG. 4 is an end view of my assembled garment hanger.

FIG. 5 is an end view of one type of hook member which may be used to support my improved garment hangers.

FIG. 6 is a section view taken along section line 6—6 of FIG. 5.

The improved garment hanger 10 of my invention generally consists of a body portion 11 formed so as to support various garments without wrinkling, and a hook member 32 adapted to support the body portion 11 in suspended relation. The body portion 11 has a trouser support section 12 and a pair of shoulder support sections 13, which are respectively adapted to provide approximately arcuate support surfaces of substantial diameter for trousers and for the shoulders of garments which are supported thereon. The body portion 11 may be stamped or otherwise formed from a single sheet of material, and may be easily assembled and disassembled without the use of external fastener means or special tools. My improved garment hanger 10 may be folded substantially flat for ease in storing or shipping, and may be quickly converted into a shape providing approximately arcuate garment supporting surfaces of substantial diameter when it is in use. The body portion 11 may preferably be stamped or otherwise fabricated from corrugated paper or corrugated cardboard, or may be similarly fabricated from inexpensive cardboard, fiberboard or other similar low cost materials

2

having the necessary bending properties and structural rigidity.

Referring more particularly to the details of construction of my invention, it is seen that the trouser support section 12 includes a partially cut-out portion 14 and a pair of vertical arcuate support members 17. The partially cut-out portion 14 is preferably "scored" or partially cut along the horizontal line between points 14a and 14b and has a plurality of substantially parallel horizontal scoring lines 16 extending the length of the lower portion of the cut-out section 14. The edge of the partially cut section 14 extending above points 14a and 14b is cut out of the body portion 11 to permit bending the partially cut-out section 14 downward along horizontal scoring lines 16. It is important that the material from which the body portion 11 is fabricated is relatively stiff, with relatively good structural strength. Such material should readily bend along the described scoring lines 16 to form a substantially arcuate trouser support surface 15 of the diameter desired, and should be sufficiently rigid to support any garments which are placed thereon without additional bending or otherwise deforming.

The approximately arcuate shape which the trouser support surface 15 assumes upon bending is additionally determined by the shape of the vertical arcuate support members 17. Such support members 17 are adapted to bend outward from the body portion 11 along substantially vertical bend lines 17b. The upper arcuate upper surfaces 17c of the vertical support members 17 are shaped such that the trouser support surface 15 will have the desired arcuate shape. FIG. 4 shows the engaged relationship of the vertical arcuate support members 17 and substantially downwardly facing surface 15a of the partially cut-out portion 14. The vertical support members 17 preferably have retaining notches 17a which engage the cut-out portion 14, as shown, to help maintain the support members 17 and cut-out portion 14 in engaged relation.

The partially cut-out portion 14 has a pair of lock tabs 19, which are adapted to extend through slot means 18 such as locking slots 18 in vertical support members 17 whereby to maintain the trouser support surface 15 in approximately arcuate shape. The locking tabs 19 may have an enlarged portion 19a and a restricted portion 19b as shown in FIGS. 1 and 2. When engaged in locking slot 18, the restricted portions 19b of the tabs 19 are in communication with the locking slot 18. The enlarged portions 19a extend beyond locking slot 18, as shown in FIG. 2, and prevent tabs 19 from becoming disengaged from slot 18. However, such enlarged portions 19a should not be so large as to prevent easy entry of tabs 19 in slot 18 during assembly of the hanger. The center portion of the partially cut-out portion 14 may preferably be maintained in the desired arcuate shape by a retainer flap 20, which extends from the body portion 11 in the manner shown.

Since the substantially vertical bend lines 17b of vertical arcuate support member 17 are approximately perpendicular to the horizontal axis about which partially cut-out section 14 is bendable to form the desired substantially arcuate trouser support surface 15, the support members 17 will prevent any substantial deformation of the trouser support surface 15 when supporting heavy garments. When the garment hanger 10 of my invention is disassembled for shipping or storage, the locking tabs 19 may be disengaged from support member 17 locking slots 18, the partially cut-out portion 14 may

rned to its original substantially flat position, and the
ical arcuate support member 17 may be folded along
d lines 17b to the substantially flat position shown in
i. 1.

he shoulder support sections 13 of my invention in-
te a pair of shoulder support surfaces 22 and a pair
upper arcuate support members 25. The shoulder
port surfaces 22 may preferably have surface scoring
s 23 emanating from a point near the center of the
er edge 11a of the body portion 11 in a downwardly
ing manner to terminate in spaced relation at the
11b of the body portion. The slopes of the scoring
s 23 will depend upon the slope which is desired for
arcuate shoulder support surfaces 22. The upper ar-
e support members 25 are bendable along substan-
straight bend lines 25a, which are preferably disposed
roximately perpendicular to the slope of the shoulder
port surface 22 when in use. The shoulder support
aces 22 are bendable along scoring lines 23 about a
ing axis to bear upon the arcuate support surfaces
of the upper support members 25 in the same man-
that the trouser support section partially cut-out por-
14 is bendable about vertical arcuate support mem-
17. The arcuate shape of the shoulder support sur-
s 22 depends on the shape of the arcuate support
aces 25b, and the position of the scoring lines 23.
upper support member retaining notches 26 engage
shoulder support surfaces 22, and are partially main-
ed in engaged relation by retainer tabs 22a. The
oulder support section locking tabs 28 engage slot-
ns in the upper support member such as locking slots
as shown in FIGS. 2 and 4. The shoulder support
ion locking tabs 28 may have enlarged portions 28a
restricted portions 28b as shown in FIG. 1. The
28 retain the shoulder support surfaces 22 in the de-
1 arcuate relation in the same manner as that de-
bed with respect to the engagement of the partially
out portion locking tabs 19 within the vertical support
ber locking slots 18. The shoulder support sections
may be further maintained in the desired arcuate re-
on by means of retainer flaps 29 located as shown in
S. 1 and 2.

use, the shoulder support sections 13 of my im-
ved garment hanger 10 provide tapered support sur-
s 22 of downwardly increasing diameter which are
ticularly well adapted to support the shoulders of
ous garments in a wrinkle free manner. The diam-
of the arcuate shoulder support surfaces 22 may be
ed by changing the number of scoring lines 23, and/or
increasing or decreasing the radius of curvature of the
er support member arcuate support surface 25b. Sim-
ly, the amount of taper may be varied by changing
relative position and slope of the scoring lines 23.
he shoulder support surfaces 22 of my improved gar-
it hanger 10 additionally preferably include strap sup-
t slots 24, which are adapted to receive and support
shoulder straps of shoulderless garments.

he body portion 11 of my improved garment hanger
is preferably supported in suspended relation by a
ble hook member 32, which may be attached to the
y portion 11 in any suitable manner. One preferred
od for attaching a hook member 32 to my garment
ger body portion 11 is illustrated in the drawings,
rein the hook member has an upper curved portion
a stem portion 34 and a lower slotted portion 35.
slotted portion 35 comprises a pair of straight, sub-
tially horizontal sides 36 and 37. The stem portion
is connected to the approximate midpoint of the upper
ected side 36. The ends of the connected side 36
ferably extend downwardly from the upper side 36 at
arcuate angle to the vertical, and then extend toward
h other substantially parallel to the connected side
as shown in FIGS. 5 and 6, to define the lower side
In the preferred embodiment, then, the lower side 37
spaced, integral extension of the upper side 36. The

body portion 11 has a pair of support tabs 30 with inner
edges 31 in substantially close relation, as shown in FIGS.
1 and 2. The support tabs 30 are bendable downward
at the lower portions 35a thereof in the manner shown
in FIG. 2. The stem section 34 of the hook member 32
is adapted to extend between the support tab inner edges
31 at the stem opening 31a, as shown in FIG. 2, such
that the support tabs 30 may be extended downwardly
between the sides 36 and 37 of the hook member slotted
portion 35. It can be seen from FIG. 2 that the slotted
portion connected side 36 extends underneath the down-
wardly bent support tabs 30, and the slotted portion lower
side 37 extends over the support tabs 30 to maintain said
tabs in the downwardly extending position shown. FIGS.
5 and 6 more thoroughly show the relation of the slotted
portion connected side 36, which is connected to the stem
portion 34, and the lower side 37. The angle at which
the lower side 37 extends downwardly from the connected
side 36 will depend upon the thickness of the sides and
upon the thickness of the material from which the body
portion 11 is fabricated. It can be seen from FIG. 2
that as the garment hanger 10 is subjected to more weight,
the support tabs 30 will tend to straighten out and extend
upwardly as in FIG. 1. However, as such tendency in-
creases, the pressure exerted upon the support tabs 30
by the slotted portion lower side 37 correspondingly in-
creases, and the support tabs 30 are more tightly engaged
by the hook member slotted portion 35. Hook retainer
notches 31b also aid in maintaining the hook slotted
portion in locked relation, as shown. The type of hook
member 32 which is used will depend upon the loads for
which the garment hanger is designed and the materials
from which the body portion is fabricated. FIG. 4
shows a double hook which may be used when larger
loads are to be expected.

It is obvious that a number of modifications can be
made in my improved garment hanger 10 without depart-
ing from the principles of the present invention. As pre-
viously mentioned, variations are permissible in the type
40 of materials used to fabricate the body portion 11, the
thickness of the body portion 11, and the type of hook
32 which may be used to support the body portion 11.
In addition, the dimensions of my invention may be
widely varied to provide a garment hanger of the par-
45 ticular size desired. Typical dimensions for my garment
hangers 10 include arcuate trouser support surface diam-
eters in excess of one inch, and shoulder support sur-
faces widening to maximum diameters in excess of one
and one-half inches.

50 As used in the present description, the term "scoring
lines" includes not only those bend lines formed by par-
tially cutting the body portion material, but also includes
bend lines formed in any deliberate manner at the sub-
stantial locations shown in the drawings and described
55 above.

The present invention may also be modified to include
just the trouser support section 12 or just the shoulder
support sections 13. Such modifications will provide
hangers of minimum cost for specialized use as trouser
60 hangers or coat hangers of minimum cost for specialized
use as trouser hangers or coat hangers where desired.
Such trouser hangers and coat hangers include just those
features of the above described and illustrated garment
hanger which are necessary for the support of the gar-
ment desired.

An additional feature of my invention is its adapta-
bility for advertising. Space 38 provides a broad surface
on which the name of the cleaning firm furnishing the
hanger and/or other suitable advertising material may
be printed, as shown in FIGS. 1 and 2.

70 It is understood that the present invention is not lim-
ited to the particular construction and arrangement of
parts herein described and illustrated, but embraces all
such modifications thereof as come within the scope of
the following claims.

I claim:

1. A garment hanger comprising in combination:
  - (a) a bendable body section having a trouser support section and a pair of shoulder support sections,
  - (b) said trouser support section including a plurality of substantially vertical arcuate support members being extendable outwardly from said body section and each having an upper arcuate support surface and slot means, and further including a partially cut-out portion being downwardly bendable about a substantially horizontal axis and having a substantially downwardly facing surface adapted to engage said vertical support member upper arcuate support surfaces for substantially their entire lengths and having an upwardly facing approximately arcuate trouser support surface, said support member upper arcuate support surfaces being adapted to maintain said partially cut-out portion and said trouser support surface in approximately arcuate shape when supporting heavy garments,
  - (c) said partially cut-out portion having tabular means for engaging said slot means in said vertical arcuate support members in fixed relation and maintaining said trouser support surface in approximately arcuate shape,
  - (d) each of said shoulder support sections including an upper support member being extendable outwardly from said body section and having an upper arcuate support surface and slot means, and further including a shoulder support surface being downwardly bendable about a downwardly sloping axis to engage said support member upper arcuate support surface for substantially its entire length, said support member upper arcuate surface being adapted to maintain said shoulder support surface in approximately arcuate shape when supporting heavy garments,
  - (e) each of said shoulder support surfaces having tabular means for engaging said upper arcuate support member slot means in fixed relation to maintain said shoulder support surface in approximately arcuate shape,
  - (f) hook means attached to said body section whereby to support said hanger in suspended relation.
2. The invention described in claim 1 wherein said arcuate shoulder support surfaces are of downwardly increasing diameter.
3. The invention described in claim 1 wherein said arcuate shoulder support surfaces are slotted to receive and support the shoulder straps of shoulderless garments.
4. The invention described in claim 1 wherein said partially cut-out portion and said shoulder support sections are scored to facilitate the approximately arcuate bending thereof.
5. The invention described in claim 1 wherein
  - (a) said body section has a pair of substantially flat support tabs,
  - (b) said support tabs have inner edges in substantially close relation and being downwardly bendable about a substantially horizontal axis at the base portions thereof, and
  - (c) said hook means has an upper curved portion, a stem section and a lower slotted portion,
  - (d) said hook stem portion being adapted to extend between said support tab inner edges and said lower slotted portion being adapted to engage said support tabs in supporting relation when said tabs are bent downward to a position substantially below said horizontal axis.
6. The invention described in claim 5 wherein:
  - (a) said hook slotted portion has a pair of straight substantially horizontal sides,
  - (b) one of said sides being connected to said hook stem portion at the approximate midpoint of said one side, and

- (c) said connected sides having opposed ends which extend downwardly therefrom at an acute angle to the vertical, and then extend toward each other substantially parallel to said connected side to define a lower side,
- (d) said support tabs being adapted to be bent downwardly over said connected side and between said connected and lower sides,
- (e) said lower side being adapted to maintain said tabs between said connected and lower sides in supported relation.
7. The invention described in claim 1 wherein tainer flaps extend from said body portion whereby engage said partially cut-out portion and said shoulder support sections and maintain said engaged elements in approximately arcuate bent relation.
8. The invention described in claim 1 wherein said vertical arcuate support means and said upper arcuate support means are slotted to receive said cut-out portion and said shoulder support surface tabular means and said shoulder support surface tabular means, respectively, and wherein said tabular means are adapted to be locked within said slots in fixed relation.
9. A trouser hanger comprising in combination:
  - (a) a bendable body section having a plurality of substantially vertical arcuate support members including a partially cut-out portion and slot means,
  - (b) said substantially vertical arcuate support members being extendable outwardly from said body section and each having an upper arcuate support surface,
  - (c) said partially cut-out portion being downwardly bendable about a substantially horizontal axis and having a substantially downwardly facing surface adapted to engage said vertical support member upper arcuate support surfaces for substantially their entire lengths and having an upwardly facing approximately arcuate trouser support surface,
  - (d) said support member upper arcuate support surfaces being adapted to maintain said partially cut-out portion and said trouser support surface in approximately arcuate shape when supporting heavy garments,
  - (e) said partially cut-out portion having tabular means for engaging said slot means in said vertical support members in fixed relation and maintaining said trouser support surface in approximately arcuate shape,
  - (f) hook means attached to said body portion whereby to maintain said hanger in suspended relation.
10. A garment hanger comprising, in combination:
  - (a) a bendable body portion having a pair of shoulder support sections,
  - (b) each of said shoulder support sections including an upper support member being extendable outwardly from said body portion and having an upper arcuate support surface and slot means,
  - (c) each of said shoulder support sections also including a shoulder support surface being downwardly bendable about a downwardly sloping axis to engage said support member upper arcuate support surface for substantially its entire length,
  - (d) said support member upper arcuate surface being adapted to maintain said shoulder support surface in approximately arcuate shape when supporting heavy garments,
  - (e) each of said shoulder support surfaces having tabular means for engaging said adjacent upper arcuate support member slot means in fixed relation to maintain said trouser support surface in approximately arcuate shape,
  - (f) hook means attached to said body section whereby to support said hanger in suspended relation.

UNITED STATES PATENT OFFICE
CERTIFICATE OF CORRECTION

Patent No. 3,162,341

December 22, 1964

George Daniel Strampe

It is hereby certified that error appears in the above numbered patent requiring correction and that the said Letters Patent should read as corrected below.

Column 2, line 28, for "upper", second occurrence, read
-- support --; column 3, line 71, for "arcuate" read
-- acute --; column 4, lines 60 and 61, strike out "of
minimum cost for specialized use as trouser hangers or
coat hangers"; column 6, line 1, for "sides" read
-- side --.

Signed and sealed this 4th day of May 1965.
